DESIGN FOR A GOBLET

Edwin W. Fuerst, Toledo, Ohio, assignor to Libbey Glass Company, Toledo, Ohio, a corporation of Ohio

Application October 30, 1936, Serial No. 65,599

Term of patent 14 years

To all whom it may concern:

Be it known that I, Edwin W. Fuerst, a citizen of the United States, residing at Toledo, in the county of Lucas and State of Ohio, have invented a new, original, and ornamental Design for a Goblet, of which the following is a specification, reference being had to the accompanying drawing, forming a part thereof.

In the drawing:

Fig. 1 is a side elevational view of a goblet showing my new design.

Fig. 2 is a top plan view thereof on a smaller scale than Fig. 1.

The characteristic feature of the design is shown in full lines.

I claim:

The ornamental design for a goblet substantially as shown and described.

EDWIN W. FUERST.
